UNITED STATES PATENT OFFICE.

JOSEPH W. ISHERWOOD, OF CHISLEHURST, ENGLAND.

CONSTRUCTION OF FLOATING VESSELS.

Application filed June 12, 1924, Serial No. 719,575, and in Great Britain July 17, 1923.

This invention relates to floating vessels especially adapted, but not exclusively, to the carriage of petroleum or other liquids in bulk and which are built in accordance 5 with what is universally known as the Isherwood system of ship construction, an example of which is illustrated in U. S. Patent #1,029,546, dated June 11, 1923.

Said vessels as is well known, are provided 10 with bulkheads to form the tanks in which the petroleum is stored, and the skin of the ship and these bulkheads are usually stiffened by longitudinal and horizontal members which have been, prior to this invention, 15 bracketed to the plating and to each other at the corners of the tank. But under the severe and complex strains to which a vessel is subjected in heavy seas, experience has shown that leaks are apt to occur at these 20 brackets, and one of the objects of this invention is to do away with these said brackets and to substitute a modified form of stiffening which will be seaworthy under the most trying circumstances, and yet, at 25 the same time, not require an excessive weight of metal.

Referring to the accompanying drawings forming a part of this specification, in which like numerals designate like parts in all the 30 views:

Figure 1 is a diagrammatic plan view of an oil carrying tank stiffened in accordance with this invention;

Figure 2 is a view of a somewhat modified 35 form of structure (stiffening at the corners of the tank);

Figure 3 is a view of a still further modified form of structure stiffening that may be used at the corners of the tank;

Figure 4 is a sectional view taken on the 40 line 4—4 of Figure 2;

Figure 5 is a sectional view on the line 5—5 of Figure 3;

Figure 6 is a view similar to Figure 1, but 45 showing a modified construction of stiffening employing brackets on the webs of the sides of the tanks;

Figure 7 illustrates a still further modified means of stiffening the tanks;

Figure 8 shows a common form of stiffening 50 the tank with the brackets heretofore employed;

Figure 9 is a diagrammatic perspective view of a portion of the sides of an Isherwood vessel fitted with a bulkhead forming 55 a part of a tank;

Figure 10 is a still further modified form of stiffening for the corners of tanks made in accordance with this invention; and

Figure 11 is a sectional view on the line 11—11 of Figure 10.

In order that the precise invention may be the more clearly understood, reference will first be had more particularly to Figures 8 and 9, and it is said:

As is well known, the general practice in the construction of these oil carrying vessels, or so called "tankers", when built on what is now known as the Isherwood system, is to provide supports for the skin 1 and deck 2 of the vessel by fitting at widely spaced longitudinal intervals strong transverse frames 3 and beams 4, which are spaced from eight to twelve feet apart, there being no intermediate transverse frames or beams between 75 the said strong transverse frames and beams hereinafter called transverses. Each of the transverse bulkheads 5 forming a wall of an oil compartment 6, and which are fitted in these tankers at longitudinal intervals of 80 from, say, twenty to thirty feet apart, takes the place of a transverse. It is further well known that in association with these transverses 3 and bulkheads 5 there are fitted in said tankers a series of longitudinal frames 85 7 and longitudinal beams 8 spaced from, say, twenty-four to thirty-six inches apart to complete the supports of the skin and deck of the ship. These longitudinal frames 7 and beams 8 hereinafter are called longitudinals.

The plating of the transverse bulkheads 5 in these tankers is further stiffened by fitting vertical webs 10 at transverse intervals of from, say, six to ten feet apart, and 95 in association with these last named members 10 there are provided a series of horizontal stiffeners 12 running transversely of the vessel, the spacing of which corresponds approximately to the longitudinals 7 of the 100 skin of the ship.

As is further well known, the strength or dimensions of the transverses 3 at the sides and at the bottom of the ship respectively are largely determined by the load they have 105 to sustain, and the strength or dimensions of the webs 10 on the transverse bulkheads are determined on the same basis.

For the purpose of comparison of strengths and in some measure in arriving 110 at the dimensions of the longitudinals of the bottom sides and deck of the ship the trans-

verse bulkhead 5 and the transverses 3 are regarded as fixed points, and in like manner the webs 10 on the transverse bulkhead are also regarded as fixed points in arriving at the size of the horizontal stiffeners 12 carried by said transverse bulkhead. In nearly all of such tank vessels, it is the well known practice to fit the bulkhead 15 at the middle line of the ship running longitudinally for the length of the oil carrying spaces. This middle line bulkhead 15 is stiffened in like manner as the sides of the ship by the transverse bulkheads 5 and the vertical webs 16 and a series of longitudinal stiffeners 17. The webs 10 and 16 on the transverse and middle line bulkheads can either be fitted on the same sides as the longitudinals and horizontals as is illustrated in Figure 8, or they can be fitted on the opposite side of the bulkheads 5 and 15, as may be desired. Likewise, in cases where for any particular purpose it is desired to place the longitudinals 7 of the skin of the ship on the outside of the plating 1, such for instance as for fendering purposes, such disposition of said longitudinals of course can be had.

Each of the longitudinals 7 at the side of the ship and the longitudinal stiffeners 17 on the middle line bulkhead 15 and likewise each of the horizontal stiffeners 12 on the transverse bulkheads are assumed to be girders having a span corresponding to the distance between their corresponding transverses or webs and having fixed supports at the points of intersection of transverses and webs.

It is further well known that at the points of junction of the transverse bulkheads 5 with the skin 1 and deck 2 of the ship the longitudinals 7 of the skin and the longitudinals 8 of the deck are each discontinued. Further, the horizontal stiffeners 12 of the transverse bulkheads 5 are likewise each discontinuous where they meet the skin of the ship, but it is the common practice to fit each of these members 7, 17, and 12 with brackets 18 to connect the parts so that they may be regarded as having fixed ends, all as will be clear from Figure 8. When these brackets are employed the distances between the transverses or webs are equal to or less than the distances between the transverses or webs and the corners of the tank compartment.

The longitudinal stiffeners 17 on the middle line bulkhead 15 are dealt with in the same manner. That is, they are connected by brackets 19 at the corners of the tank with the transverse stiffeners 12. But experience has shown that these said brackets 18 and 19 which might be described as corner brackets are not only expensive to fit but constitute stiffened areas that are conducive to leakage at their points of riveting when a vessel is stressed in heavy seas

or when the parts are subjected to heavy loads as intimated above.

Therefore, the object of this invention, as above stated is to eliminate these corner brackets 18 and 19 or many of them, without sacrificing the strength of the bracing structure and without requiring a prohibitive weight of metal. To accomplish this, I proceed as follows: The longitudinals 7 and 8 of the skin and deck plating and the horizontals 12 and 17 of the transverse and middle line bulkheads are stopped short of the corners of the tanks as is usually done in the present practice of building according to the Isherwood system. But according to this invention, these stiffening members are not provided with any corner brackets 18 and 19 at all. Instead of said brackets, as will be clear from Figure 1, I support the longitudinals 7 of the skin 1, and the longitudinals 8 of the deck, Figure 9, as well as the horizontals 17 of the middle line bulkhead 15, preferably by two or more transverses or webs 16 in each oil tank, and fit preferably two or more vertically disposed webs 10 on the transverse bulkheads between the middle line bulkhead 15 and the sides 1 of the ship.

I so dispose these transverses or webs 10 and 16 that the distances 25 between the said webs or transverses are greater than the lengths 26 of the projecting end spans of the longitudinals 7 and 17 and of the horizontal members 12. In other words, the lengths of the ends 26 of the longitudinals or horizontals, instead of being equal to or greater than the lengths 25, are always less than said lengths 25, and in making the calculations of strengths, they are treated as beams whose portions 26 are fixed at said transverses or webs and are not to be connected by brackets. Said ends 26 being unconnected by brackets, may now be calculated and made of such dimensions or cross sections as will cause their strength to be substantially the same as the strength of the portions 25 of the same stiffener located between the points supported or assumed to be fixed by the transverses or webs.

No arbitrary length of projecting ends 26 of the longitudinal or horizontal stiffeners, however, can be fixed in relation to the distance 25 between the points of support given by the transverse webs 10 or 16, for this ratio may vary from 40% to 80%, or thereabouts, depending on the arrangement adopted whether the end of the projecting portions is regarded in the calculations as free or simply supported.

It will, however, be obvious that by increasing the distance 25 between a pair of transverses 16 or webs 10, so as to lessen the lengths of the projecting portions 26, said longitudinals or horizontals must be substantially increased in size or weight as

compared with those in association with equally spaced transverses or webs but these increases will be equalled by the saving of weight due to the elimination of corner 5 brackets.

It should also be understood that the lengths 26 of the projecting portions of the stiffening members can be increased by the fitting of supporting brackets such as 100 to 10 the webs 16, as shown in Figure 10, and that the lengths of the horizontal spans 25 between points of support can also be increased by the fitting of supporting brackets 30 to the transverses or webs and longitudinals or horizontals, as illustrated in Figure 6.

The projecting portions 26 of the longitudinals or horizontals can also be reinforced by the fitting of a stiffening, or reverse bar 20 28, see Figure 2, if it is desired to maintain a more uniform spacing of the transverses or webs. In vessels where the oil tanks are of short lengths one transverse 32 might be fitted on each side in each tank, see Figure 25 7, and in such cases, the projecting ends 26 of the longitudinals which are unconnected by brackets to the transverse bulkheads 5 might be treated in making the calculations as free or supported as desired. The projecting portions can also be strengthened as 30 before described by the fitting of brackets 47 at either or both sides of the transverses and webs.

The middle line bulkhead and transverse 35 bulkhead can be likewise dealt with in like manner.

It is found that the dimensions of a member such as 12 or 17 which was so disposed as to make its middle portion 25 equal to or 10 less than its end portion 26, and which requires a bracket at its end, would not be suitable for another member 12 or 17 when the latter's supports 16 and 10 are so spread as to make its middle portion 25 greater 45 than its end portions 26, and which is not to be fitted with a bracket, as is the case in this invention. In other words, the lengths of the parts 25 and when not bracketed 26 as well as their scantlings will vary 50 with the dimensions of the tanks and conditions of service.

When it is desired to maintain the full longitudinal strength of the structure, the plating 1 can be increased in thickness if desired in the way of the unbracketed ends 26 of the longitudinals, or plates of metal 35 called doublings, see Figures 1, 2, 3, 6, 7, 10 and 11, can be fitted to the plating in the way of the transverse bulkheads as shown. 60 In the case where fenders are fitted to the outside of the skin, the fender bars can be utilized to act for the same purpose. When either of these constructions are adapted 75 the ratio of the length 26 of the projecting portion of the stiffener as compared with the

length 25 of the stiffener between the webs or transverses can be increased beyond the lower limit of 40% above stated. The unbracketed ends 26 of the longitudinals or horizontals can when desired be fitted with 70 back bars 50 and 51, Figures 10 and 11, attached to the plating, and to the longitudinal or horizontal members, and these will have the effect of reducing the length of the doublings 35 when they are fitted. 75

The construction shown in Figure 2 is the same as that shown in Figure 1, with the addition of the reinforcing member 28, at the ends of the longitudinal and horizontal stiffeners 7, and 12, as illustrated. 80

The same remarks apply to Figure 3, except the reinforcing members 36 and 37 are somewhat differently placed. The construction of Figure 6 is the same as in Figure 1, except the brackets 30 are fitted to the transverses 16 and to the webs 10 as illustrated. The construction illustrated in Figure 7 is the same as that shown in Figure 1, except only one transverse 32 is fitted between the bulkheads 5 and only one web 46 is fitted to 90 the bulkheads 5 as shown. Brackets 47 may or may not be fitted to transverses 32 and webs 46, as desired.

The construction shown in Figure 10 is the same as that shown in Figures 1 and 2 except the back bars 50 and 51 are differently placed, and attached to both the longitudinals and plating. 95

What is claimed is:

1. In a liquid cargo carrying vessel provided with a tank having walls, the combination of longitudinally and horizontally disposed stiffening members secured to said walls and of lengths insufficient for their ends to reach to the corners of said tank; and vertically disposed stiffening members secured to said walls and to said first named members, the ends of said stiffening members being devoid of brackets. 100

2. In a vessel provided with a tank adapted to carry a liquid cargo and having vertically disposed walls the combination of horizontally disposed stiffening members rigid with said walls and of lengths insufficient to reach the corners of said tank; and vertically disposed stiffening webs secured to said walls and to said first named stiffening members between the ends of the latter, said webs being so spread that the lengths of said ends beyond said webs are less than the distances between said webs. 110

3. In a tank for an oil carrying vessel, the combination of longitudinally and horizontally disposed stiffening members rigid with the walls of said tank; and a plurality of vertically disposed stiffening members, on each wall, between which and beyond which a plurality of said stiffening members extends, said vertically disposed members being so spaced that the extending ends of 125 130

said horizontally disposed members are shorter than the space between said vertically disposed members, and said ends being of a length insufficient to reach the corners of said tank.

4. In a liquid cargo carrying vessel provided with a tank having walls, the combination of longitudinally and horizontally disposed stiffening members secured to said walls and whose ends are unbracketed and of lengths insufficient to reach to the corners of said tank; and vertically disposed stiffening members secured to said walls and to said first named members.

15 5. In a vessel provided with a tank adapted to carry a liquid cargo and having vertically disposed walls the combination of horizontally disposed stiffening members rigid with said walls whose ends are free from 20 brackets, and of lengths insufficient to reach the corners of said tank; and spaced vertically disposed stiffening webs secured to said walls and to said first named stiffening members between the ends of the latter, the 25 lengths of said ends beyond said webs being less than the distance between said webs.

6. In a tank for an oil carrying vessel, the

combination of longitudinally and horizontally disposed stiffening members rigid with the walls of said tank; and a plurality of 30 vertically disposed stiffening web like members on each wall between which and beyond which a plurality of said stiffening members extends, the extending ends of said members being unbracketed and shorter than the space 35 between said vertically disposed members, and said ends being of a length insufficient to reach the corners of said tank.

7. In a liquid cargo carrying vessel provided with a tank having walls and carried on a 40 deck, the combination of longitudinally disposed stiffening members secured to one of said walls, the ends of said members terminating short of the adjacent tank walls and 45 being devoid of brackets; transversely disposed stiffening members secured to one of said walls; and spaced stiffening members crossing said first named members, forming spans between them which are longer than the unbracketed ends on each side of said 50 stiffening members.

In testimony whereof I affix my signature.

JOSEPH W. ISHERWOOD.
